UNITED STATES PATENT OFFICE.

ELLA K. STORER, OF AKRON, OHIO.

FLY-CATCHER.

No. 848,865.

Specification of Letters Patent.

Patented April 2, 1907.

Application filed December 21, 1906. Serial No. 348,937.

To all whom it may concern:

Be it known that I, ELLA K. STORER, a citizen of the United States, residing at Akron, in the county of Summit and State of Ohio, have invented new and useful Improvements in Fly-Catchers, of which the following is a specification.

This invention is a device for catching flies and other insects; and the object thereof is to provide a simple and effectual device whereby the ordinary insects, such as flies, &c., may be caught and retained. Heretofore the ordinary means for destroying such insects has consisted of poison, various forms of fly-traps, and adhesive paper, all of which, while possessing some merit, are open to a number of objections which this invention is designed to overcome.

With the foregoing and other objects in view the invention consists in the novel construction, combination, and arrangement of parts constituting the invention to be hereinafter referred to and illustrated in the accompanying drawing, which forms a part of this specification, in which is shown the preferred embodiment of the invention; but it is to be understood that changes, variations, and modifications can be resorted to which come within the scope of the claim hereunto appended.

The drawing presented is a central longitudinal section of my device.

In the drawing the reference-numeral 1 indicates a base, preferably of metal, and of sufficient weight to properly maintain the device against overturning. The upper portion of this base is provided with a saucer-shaped depression 2, from the center of which extends upwardly a pin 3, secured to the base 1 by any preferred means. This pin 3 is preferably tapered, with the smaller end at the top, for a purpose to be later described. This invention mainly resides in keeping this pin 3 coated with an adhesive or mucilaginous substance which will attract the flies and be of such a consistency as to prevent their escape therefrom in the same manner that sticky fly-paper is employed. In order to coat this pin 3 with an adhesive substance, and to renew the coating as frequently as it becomes ineffective or to renew it because of the accumulation of fly carcasses thereon, I employ a small tank 4, having perforations 5 and 6 in the top and bottom respectively. On the floor of this

tank I place a rubber washer 7, having a central perforation considerably less in diameter than the diameter of the pin 3, so that it will constantly grasp this pin and serve to act as a closing medium for the tank, thereby keeping any fluid contained therein from escaping therefrom. Within this tank 4 I place some adhesive or mucilaginous substance, (designated in the drawing by the reference-numeral 8,) and which is kept from escaping by reason of the rubber washer 7.

In operation the tank is passed downward over the top of the pin 3 until the upper point thereof has passed through the perforation in the rubber washer 7. Then a desired quantity of adhesive or mucilaginous substance is poured into the tank and the tank forced downward to near the base of the pin 3, during which operation the adhesive or mucilaginous substance adheres and completely coats the exterior of the pin 3.

In view of the fact that it is almost impossible to maintain a fly-catching substance in proper condition and sufficiently sticky to prevent their escape a new coating may be placed on the surface of the pin 3 at any time by raising and lowering the tank 4. If at any time the pin 3 becomes too abundantly covered with adhering flies, the raising of the tank 4 will serve to remove the flies therefrom. If for any reason a surplus of adhesive or mucilaginous substance runs down the pin 3 it will be caught in the saucer-shaped depression 2 in the base.

It will be seen from the foregoing that this device affords simple, neat, and reliable means for catching flies, as experience has shown that flies have a constant tendency to light on small rods, wires, chandeliers, &c., in preference to lighting on sheets of sticky fly-paper. Another feature in favor of this device is its lasting qualities, for the fluid may be renewed as often as needed, and there is nothing about the utensil which will wear out.

Having thus described my invention, what I claim, and desire to secure by Letters Patent, is—

The combination in a device of the class designated, of a base provided with a concaved depression in its upper portion, a tapering pin mounted on said base within the confines of said depression, a tank provided with perforated top and bottom portions, the perforations in these portions being larger

than the pin at its largest point, a rubber washer in the bottom of said tank provided with a perforation sufficient to permit the pin to pass therethrough and be frictionally engaged thereby, and a quantity of adhesive or mucilaginous liquid in said tank above said rubber washer, all constructed substantially as shown and for the purpose stated.

In testimony whereof I have hereunto set my hand in presence of two subscribing witnesses.

ELLA K. STORER.
